N-SUBSTITUTED 4,6-DIAMINO METANILIC ACIDS AND THE CORRESPONDING NITRO DERIVATIVES

Robert C. Gunther, Easton, Pa., assignor to General Aniline & Film Corporation, New York, N. Y., a corporation of Delaware

No Drawing. Application October 29, 1949,
Serial No. 124,501

5 Claims. (Cl. 260—509)

1

The present invention relates to N-substituted 4,6-diaminometanilic acids in which the amino group in the 4-position is substituted by hydroxyalkyl and to the nitro intermediates from which said metanilic acid compounds are derived.

In the copending application, Serial No. 640,382, filed on January 10, 1946, by Willy A. Schmidt and Vsevolod Tulagin, now United States Patent No. 2,486,440, there is described the production of azine dye images by color forming development while utilizing inter alia as the color developer derivatives of 2,4-diamino-aniline. While these color developers have been found to be effective in producing the desired dyestuff images in the presence of the usual color forming components, it is noted that they have a tendency to be adsorbed to silver halide grains of the photographic emulsions, thereby making it difficult to effect the complete removal thereof from the emulsion by washing after development. Furthermore, said compounds have been observed to cause stain in the reduction of silver halides, particularly when such reduction takes place in the absence of a color former.

Difficulties have also been encountered in the production of yellow dye images by the utilization of the aforeslated developers. Experience has shown that when using such developers with color formers generally employed for the production of yellow azomethine images, i. e., open chain keto methylene compounds, magenta images rather than yellow images ensue. These magenta images may be subsequently converted into yellow images but only by a separate step involving a treatment with an alkali.

It has now been discovered that the production of azine dye images can be effectively carried out without the aforesaid objections if there be employed as color developers derivatives of 4,6-diamino metanilic acid in which the amino group in the 4-position is substituted by a hydroxyalkyl group. Inasmuch as said compounds are capable of effecting the reduction of silver halides including latent images without the formation of stain, they may also be employed as developers for black and white images.

These developers also have the unique property of yielding yellow dye images directly when employed to develop a developable silver halide emulsion in the presence of an open chain keto methylene compound. They are therefore admirably suited for the production in one development step of azine dye images in the three subtractive colors.

Said metanilic acid derivatives and the nitro intermediates from which they are derived are

2

novel compounds. The nitro intermediates are per se yellow dyestuffs having excellent affinity for wool and nylon.

Such metanilic acid derivatives and the nitro compounds serving as intermediates for their production and as new dyestuffs constitute the purposes and objects of the present invention.

The new compounds contemplated herein are typified by the following structural formula:

10

15

wherein R is hydrogen or alkyl, i. e., methyl, ethyl, propyl, butyl, amyl, or the like, R₁ is an acyclic aliphatic radical such as alkyl as above, carboxyalkyl, such as carboxymethyl, carboxyethyl, and the like, hydroxyalkyl, such as hydroxymethyl, hydroxyethyl, hydroxypropyl, and the like, an aromatic radical of the benzene series, that is a monocyclic carbocyclic aromatic radical, such as phenyl, toluyl, carboxymethylphenyl, carboxyethylphenyl, carboxymethoxyphenyl, carboxyethoxyphenyl, hydroxymethylphenyl, hydroxyethylphenyl, hydroxymethoxyphenyl, hydroxyethoxyphenyl, and the like, R₂ is hydroxyalkyl, and R₃ is nitro or primary amino.

Examples of compounds illustrative of those within the general formula are the following:

35

40

4-(β-hydroxyethylamino)-6-(4'-carboxy-methoxy phenylamino) metanilic acid and the corresponding nitro compound

45

50

4-(hydroxymethylamino)-6-(4'-methoxy phenylamino) metanilic acid and the corresponding nitro compound

55

3. - 4,6-di(β-hydroxyethylamino)-metanilic acid and the corresponding nitro compound
4. - 4-(β-hydroxyethylamino)-6-phenylamino-metanilic acid and the corresponding nitro compound
5. - 4-(β-hydroxyethylamino)-6-(β-sulfoethylamino)-metanilic acid and the corresponding nitro compound
6. - 4-(β-hydroxy-β-methyl-ethylamino)-6-phenylamino-metanilic acid and the corresponding nitro compound
7. - 4-(α-di-[hydroxymethyl]-ethylamino)-6-(3'-ethoxy phenylamino)-metanilic acid and the corresponding nitro compound
8. - 4-(β-hydroxy ethylamino)-6-methylamino-metanilic acid and the corresponding nitro compound
9. - 4-(hydroxymethylamino)-6-(methyl phenylamino)-metanilic acid and the corresponding nitro compound
10. - 4-(β-hydroxybutylamino)-6-dimethylamino-metanilic acid and the corresponding nitro compound
11. - 4-(β-hydroxyethylamino)-6-carboxymethylamino-metanilic acid and the corresponding nitro compound
12. - 4-(β-hydroxyethylamino)-6-(N-phenyl-N-carboxymethyl)amino-metanilic acid and the corresponding nitro compound
25. The aforementioned compounds are prepared by reacting in the proper sequence 2,4-dichloro-5-nitrobenzene sodium sulfonate with the amines desired to be introduced into the 2- and 4-positions of the benzene ring, and then effecting reduction of the nitro group to an amino group.
30. The preparation of the compound by the aforementioned method is made possible by the fact that the chlorine atom in the 4-position is more easily replaced by an amino group than the chlorine atom in 2-position. Thus by refluxing the 2,4-dichloro-5-nitrobenzene sodium sulfonate with an equivalent of an amine, the chlorine atom in 4-position is selectively replaced by such amine.
35. By subsequently treating the resulting compound with the same or a different amine under more elevated temperatures, i. e., temperature ranging from 110 to 150°C., the chlorine atom in 2-position is replaced by the amine.
40. The following examples will serve to illustrate the invention but it is to be understood that the invention is not restricted thereto. The parts are by weight unless otherwise stated.
45. *Example I*
50. Into a 1-liter, 3-necked round-bottom flask equipped with a mechanical stirrer and a reflux condenser was placed 147 parts of the sodium salt of 2,4-dichloro-5-nitrobenzene sulfonic acid, 31 parts of ethanalamine and 54 parts of sodium carbonate dissolved in 250 parts of water. After
55. the stirrer was started, the contents of the flask were gently refluxed for 10 hours. 240 parts of 30% sodium chloride solution were added to the hot reaction mixture and the flask was then cooled in an ice bath. The precipitated orange
60. solid was collected by filtration, washed with a small amount of water, and dried overnight at 80-90°C.
65. A glass interliner for an Aminco shaking type bomb was charged with 95.6 parts of the 2-chloro-4-(β-hydroxyethylamino)-5-nitrobenzene sodium sulfonate (prepared as above), 30 parts of aniline and 34 parts of sodium carbonate dissolved in 200 parts of water. The liner was sealed in the bomb and the bomb shaken at
70. 140°C. for 15 hours. The bomb was cooled and the solid removed from the interliner with small amounts of hot water. 300 parts of 30% sodium chloride solution were added with vigorous stirring of the mixture and the whole was then cooled in an ice bath for several hours. The pre-

5

precipitated solid was collected by filtration, washed with 50 parts of water, and then digested with 200 parts of ethanol. The product was again collected on a filter and dried overnight at 60° C. in a vacuum oven.

10 parts of 2-phenylamino-4-(β -hydroxyethylamino)-5-nitrobenzene sulfonic acid (prepared as above) were added portion-wise to a boiling solution of 40 parts of sodium hydrosulfite in 222 parts of 10% sodium hydroxide. After reduction is complete, a small amount of decolorizing carbon is added to the solution. The mixture is boiled vigorously for several minutes and then filtered rapidly through a fluted filter. The compound was then isolated from the clear filtrate as the inner salt by acidification with glacial acetic acid. The mixture was cooled in an ice bath for several hours, the inner salt collected on a filter and washed with water. The product was then dried six hours at 65° C. in a vacuum oven and constituted the 4-(β -hydroxyethylamino)-6-phenylamino-metanilic acid.

Example II

The procedure is the same as in Example I excepting that the aniline is replaced by 56 parts of p-amino phenoxy acetic acid.

The product produced is 4-(β -hydroxyethylamino)-6-(4'-carboxy-methoxy phenylamino)-metanilic acid.

Example III

The procedure is the same as in Example I excepting that the ethanolamine is replaced by 24 parts of methanolamine and the aniline by 41 parts of p-methoxy aniline.

The compound obtained is 4-(hydroxymethylamino)-6-(4'-methoxyphenylamino) - metanilic acid.

Example IV

The process is the same as in Example I excepting that the aniline is replaced by 20 parts of ethanolamine.

The product obtained is 4,6-di-(β -hydroxyethylamino)-metanilic acid.

Example V

The procedure is the same as in Example I excepting that the aniline is replaced by 42 parts of taurine.

The product obtained is 4-(β -hydroxyethylamino)-6-(β -sulfo-ethylamino)-metanilic acid.

Example VI

The procedure is the same as in Example I excepting that the ethanolamine is replaced by 38 parts of isopropanolamine.

The product obtained is 4-(β -hydroxy- β -methylethylamino) - 6 - phenylamino metanilic acid.

Example VII

The procedure is the same as in Example I excepting that the ethanolamine is replaced by 53 parts of 2-amino-2-methyl propane diol (1.3) and the aniline by 46 parts of m-methoxy aniline.

The product obtained is 4- α -di-(hydroxymethyl) - ethylamino - 6 - (3' - ethoxy phenylamino)-metanilic acid.

Example VIII

The procedure is the same as in Example I excepting that the aniline is replaced by 10 parts of methylamine.

The product obtained is 4-(β -hydroxyethylamino)-6-methylamino metanilic acid.

6

Example IX

The procedure is the same as in Example I excepting that the ethanolamine is replaced by 24 parts of methanolamine and the aniline by 36 parts of N-methyl aniline.

The product obtained is 4-(hydroxymethylamino)-6-(methylphenylamino)-metanilic acid.

Example X

The procedure is the same as in Example I excepting that the aniline is replaced by 50 parts of N-phenylamino acetic acid.

The product obtained is 4-(β -hydroxyethylamino)-6-(N - phenyl-N-carboxymethylamino)-metanilic acid.

As stated, the aforementioned metanilic acid derivatives are characterized by their marked ability to effect reduction of silver halides, i. e.,

latent images, reverse images, bleached images, and the like, without formation of objectionable stain. As a consequence of the reducing power they may be employed for development of black and white images or for the production of color images.

One of the most notable properties of the aforementioned metanilic acid derivatives, however, is their ability to directly yield yellow dye images. This result is achieved when employing the de-

velopers to develop a developable silver halide emulsion in the presence of an open chain keto methylene compound even though the emulsion during a subsequent processing step be treated with an acidic bleach bath as is usual in the processing of film to azine dye images. In other words, whereas the formerly employed, 2,4-di-amino anilines only yielded yellow images, as the result of a subsequent alkaline treatment, the de-

velopers contemplated herein yield such images directly and without such subsequent processing with an alkaline bath. As a consequence such developers very materially contribute to the utilization on a commercial scale of the azine method for processing film in the three subtractive colors.

The yellow dyes obtained by color development with my developers appear to be true azines. Thus they withstand treatment with an acid bisulfite whereas yellow azomethines do not. Furthermore they are not split by strong mineral acids as happens with the yellow azomethines. Such yellow dye images have excellent lightfastness and brilliance and they adequately complement the magenta and cyan dyes produced by the azine methods.

The color formers employed for producing the dye images are those used in the production of color developed images, i. e., those containing aromatic-primary amino, phenolic hydroxyl or active methylene groups.

The nitro intermediates from which the metanilic acid derivatives are produced are novel yellow dyestuffs having a high affinity for wool and nylon.

Where used herein, the term "the corresponding nitro compound" is intended to mean the nitro derivative from which the metanilic acid is produced by reduction of the nitro group.

The present application is a continuation-in-part of my application Serial No. 793,532, filed December 23, 1947, now abandoned, entitled "Color Developers for the Production of Phenazonium Dyestuff Images," and my application Serial No. 101,913, filed January 28, 1949, and entitled "Color Developers for the Production of

Azine Images," is now U. S. Patent 2,570,116, is-
sued October 2, 1951.

Attention is directed to the later filed case for
examples of the use of the metanilic acid deriva-
tives in the production of azine dye images.

Various modifications of the invention will oc-
cur to persons skilled in this art, and I therefore
do not intend to be limited in the patent granted
except as necessitated by the appended claims.

I claim:

1. Compounds of the following structural for-
mula:

wherein R is a member selected from the class
consisting of hydrogen and lower alkyl radicals,
R₁ is a member selected from the class consisting
of lower acyclic aliphatic radicals and a mono-
cyclic carbocyclic aromatic radical, R₂ is hydroxy
lower alkyl, and R₃ is a member selected from
the class consisting of nitro and primary amino.

2. 4 - (β -hydroxyethylamino)-6-phenylamino-
metanilic acid.

3. 4 - (β - hydroxy - β - methylethylamino) - 6-
phenylamino metanilic acid.

5 4. 4 - (β - hydroxyethylamino) - 6-methylamino
metanilic acid.

5. 4-(hydroxymethylamino)-6-(methylphenyl-
amino)-metanilic acid.
